(57) **CLAIM**

The ornamental design for a vehicle rear bumper, as shown and described.

DESCRIPTION

FIG. 1 is an upward perspective view of the vehicle rear bumper;

FIG. 2 is a front elevational view;

FIG. 3 is a bottom plan view;

FIG. 4 is a top plan view;

FIG. 5 is a side elevational view taken from the right side of FIG. 2; and,

FIG. 6 is a rear elevational view.

The broken lines shown throughout the drawing are for illustrative purposes only and form no part of the claimed design.
